UNITED STATES PATENT OFFICE

CECIL CHARLES BRINTON, OF KIDDERMINSTER, ENGLAND, ASSIGNOR OF ONE-HALF TO
BRINTONS LIMITED, OF KIDDERMINSTER, ENGLAND, A BRITISH COMPANY

JACQUARD LOOM FOR WEAVING PILE CARPETS

Application filed January 30, 1929, Serial No. 336,172, and in Great Britain May 22, 1928.

This invention has reference to Jacquard looms for weaving pile carpets and other figured pile or tufted multi-color fabrics and relates in particular to looms wherein the 5 yarn carriers are operated by a differential-lift jacquard for selecting the colors from which tufts are cut for conveyance into the fell of the cloth; the said yarn carriers being connected by wires or cords with the lifters in the differential-lift mechanism which is 10 actuated by the jacquard in such a way that the blank or perforation on the jacquard card corresponding with a certain color causes the carrier to be lifted until that color is at right 15 height or position in the loom for the cutting off and transference of the tuft into the fell of the cloth.

In carpet-weaving looms of the kind known in the trade as the Brinton Axminster loom, 20 the colored tuft-yarns are conveyed and located in vertical superimposition (i. e. with the various colors one over the other) into vertically-displaceable yarn-carriers, and the differential lifting or displacement of these 25 carriers is controlled through lifters by a jacquard which, as hitherto constructed, comprises a battery of horizontal needles working in guide-holes in a stationary needle-plate and arranged transversely to the loom 30 in a series of vertical rows, each containing a number of needles corresponding to the number of jacquard-controlled colors in the yarn carriers. Each such vertical row of horizontal needles is associated with a set of 35 lifter-pegs (equivalent in number and spacing to the needles) which are slidably carried horizontally in a guide-brass attached to a yarn-carrier lifter; the arrangement being such that when one of the horizontal 40 needles is permitted by the jacquard to be operated or displaced in its needle-plate by the action of the jacquard grid, this displaced needle imparts a corresponding horizontal movement to its complementary lifter-peg, 45 causing the latter to be projected beyond its brass into the path of an ascending lifting bar or straight-edge that brings about the raising of the lifter and its yarn carrier through the prescribed distance for correctly 50 positioning the selected yarn-color for cut-

ting off and transference into the fell of the carpet. The distance wherethrough each yarn carrier is lifted during any given cycle of the loom, and the consequent selection of the color, is thus controlled or determined by 55 the position of the projected lifter-peg in relation to the stroke of the straight-edge, or by the distance through which the straight-edge has to rise before engaging under the projected peg and picking up the lifter. 60

Now in the interests of strength and durability, it is desirable that the lifter-pegs (which usually and preferably are circular in section) should be of substantial dimensions to enable them to stand up to the repeated impact of the yarn-lifting straight-edge and to the wear occasioned by their reciprocating motion in the brasses, but the use of pegs of substantial section has hitherto involved consequential disadvantage in that 65 the necessity of providing sufficiently-thick guide-brasses requires excessive lateral space for their accommodation in the jacquard and this same consideration also imposes limitations on the pitch of the weave or on the number of tufts per lateral inch that can be woven into the carpet. It has, therefore, been proposed, with a view to cutting down the jacquard width in relation to the width of the other parts of the loom, to use pegs of rec- 70 tangular section, but such pegs have been found to be difficult of manufacture and unreliable in operation. In fact, the problem of constructing an efficient and durable close-pitch jacquard of substantially the same 75 width as the carpet to be woven is one for which no adequate solution has hitherto been found, and in known constructions, such as in the Brinton loom above mentioned, where the horizontal needles are arranged in a single 80 battery and the whole of the lifter brasses are disposed in one row across the width of the loom, the necessity of providing lifter-pegs and guide-brasses of adequate dimensions has limited the weaving pitch to a maximum of seven tufts per inch and resulted in the jacquard taking up a lateral space approximating to double the carpet-width capacity of the loom; the ratio of jacquard 85

90

95

100

width to maximum carpet width being an increasing or cumulative one.

The present invention proposes a solution for the problem referred to in that, whilst enabling lifter pegs of substantial section to be housed and guided in brasses of adequate dimensions, it provides for the construction and mounting of a close-pitch jacquard within a much smaller lateral space than has hitherto been possible; in fact, the invention 10 enables the construction of a strong and durable jacquard that can be built into a space of substantially same width as the maximum width of carpet the loom is capable of weaving (however wide that carpet may be) and 15 enables the production of closer pitch weave containing, for example, nine tufts per lateral inch.

According to the said invention, and to 20 realize the advantages above referred to, it is proposed so to dispose the peg-guides of the yarn-carrier lifters as to locate the lifter-pegs in separated and parallel or superimposed horizontal rows or series (preferably by arranging the guides of alternate lifters in 25 staggered relationship) and to distribute the horizontal jacquard needles into correspondingly-separated and superimposed batteries or groups, so that the needles of each battery 30 operate to control the lifter pegs in the complementary row of guides. It is also proposed to arrange for the displacement and return of the needles by providing a separate group or series of impact-bars in the jacquard 35 grid, and a separate dabbing-board, to each needle-battery; also to provide a separate lifting-bar for picking up or co-operating with the legs pertaining to each row of guides, although the control of the separated batteries of horizontal needles from the jacquard 40 cards may be, and preferably is, effected by a system of vertical needles that are arranged in a single battery or group, but are so constructed as to permit of their effective mounting and operation within the lateral space 45 available for their accommodation.

The grouping of lifter pegs and horizontal needles in accordance with the invention enables the use of narrower yarn carriers and 50 the consequent closer pitching of the tuft-grippers and permits of the construction of a loom that will weave a fabric of corresponding closer or finer pitch, and also renders it possible to reduce the overall width of the 55 jacquard without sacrifice of lifter-peg section and guide-brass thickness, and further, the invention enables the strengthening, in the manner hereafter described, of certain parts of the jacquard which are subjected to 60 considerable impact-shock and wear in operation, such, for instance, as the lifter comb and the lifter-stops that co-operate with the said comb for determining the "at rest" positions of the lifters and yarn-carriers.

65 An application of the invention to the jac-

quard mechanism of an Axminster carpet-loom is hereinafter described in detail with reference to the accompanying drawings, in which

Figures 1 and 1^a show, partly in section and partly in side elevation, the general arrangement of the jacquard mechanism as mounted in the loom; the construction being one in which the lifter-peg guide-brasses of the alternate yarn-carrier lifters are staggered 70 to dispose the said brasses, and the vertical rows of pegs housed therein, in two different horizontal planes, and in which the horizontal needles are arranged in two separate batteries spaced apart vertically to correspond to the 75 spacing of the two rows of lifter-brasses. The view also shows the arrangement of the needle-operating bars of the grid in two groups and the duplication of the dabbing boards and lifting-bars or straight-edges. The particular jacquard illustrated is designed for use with frames up to eight colors, or to control the weaving of fabric containing a maximum of seven pattern-colors in 80 addition to the ground color, each lifter being, for that purpose, provided with seven lifter pegs corresponding to the seven lower or jacquard-controlled pattern yarns contained in the yarn-carriers to which the lifters are respectively connected.

Figure 2 is a view showing the grid with its two vertically-separated sets of needle-operating bars as seen from the inner or rear face of the said grid.

Figure 3 is a perspective view showing, upon an enlarged scale, two pairs of yarn-carrier lifters with their complementary lifter-peg guide-brasses and a portion of the top and bottom comb-plates whereby the said lifters are guided in their vertical movements and are also suspended, when in their "at rest" positions, from the said top comb-plate. The view also shows the staggered disposition that locates the guides of the alternate lifters in two different and vertically-spaced horizontal rows.

Figure 3^a shows in elevation and edge view an assembly of four lifters, with the whole of the pegs of each lifter projected beyond the edge of their guide-brass.

Figure 4 shows elevations of an adjacent pair of lifters and an edge view of one of them, and illustrates the formation given to their upper or suspension ends and the "at rest" stops attached thereto.

Figure 5 is a plan view, on an enlarged scale, of a portion of the bottom comb for guiding the lifters.

Figure 6 is a similar view of a part of the top comb plate that also guides the lifters and provides for their suspension in their "at rest" positions.

Figure 7 is an elevation of the vertical needle box.

Figures 8 and 9 are an elevation and plan

of an end portion of the said needle box upon an enlarged scale, Figure 8 showing two of the vertical needles suspended in their "at rest" positions from the stop-pins of the box.

Figure 10 is a cross section of the box on the dotted line 10—10, Figure 8.

Figure 11 shows a plan of a portion of the bottom guide-plate for the vertical needle assembly.

Figure 12 shows in elevation a part of the vertical needle assembly and complementary parts of the two batteries of horizontal needles.

Figure 13 shows a set of the vertical needles embodied in the jacquard for controlling seven pattern colors as illustrated, the seven needles on the right of the figure being those which control a like number of needles in the upper horizontal battery, whilst the seven needles on the left control corresponding horizontal needles in the lower battery.

Figure 14 is a view showing, on an enlarged scale, the means provided for suspending the vertical needles in their "at rest" positions from the stop-pins in the needle-box.

The same letters of reference indicate corresponding parts in the several figures of the drawings.

In the jacquard illustrated, which is mounted in the head of the loom in substantially the usual position, the yarn-carrier lifters *a*, *b*, are slidably suspended, by stops *a*¹, *b*¹ fixed to their upper ends, from a top comb *c*² housed in the upper rear part of the jacquard frame as shown in Figure 1, and each lifter embodies a peg-guide brass *a*², *b*² fitted with seven horizontally-slidable lifter pegs *b*³ corresponding to the seven jacquard-controlled tuft-yarn colors in the yarn carrier connected to such lifter. The guide-brasses of the alternate lifters *a* have, however, a different location to the brasses of the intermediate lifters *b* so that when the lifter system is assembled in the loom, the brasses *a*² pertaining to the lifters *a* are disposed in a horizontal row or series which is vertically spaced or separated from the row of brasses *b*² pertaining to the lifters *b*. This disposition of the alternate guide-brasses is shown in Figures 3 and 3^a in an assembly of four lifters and is repeated throughout the whole width of the lifter assembly, and since, in effect, it enables two lifter-brasses of adequate thickness for housing pegs of substantial section to be accommodated in a lateral space which, in an ordinary jacquard, would only accommodate a single brass, it directly enables the construction of a close-pitch jacquard whose over-all width does not exceed, or materially exceed, the maximum width of carpet the loom is designed to produce. The two rows of brasses on the alternate lifters are separated or spaced vertically to a distance equal

to or exceeding the working stroke of each individual lifter so that either lifter of the set *a* carrying the lower brasses *a*² can be raised its maximum height without its brass fouling the brasses *b*² of the adjacent lifters *b*.

For adapting the jacquard needle system to this construction and disposition of lifter-brasses, the horizontal needles are arranged in two batteries or groups marked respectively *c* and *d* in Figure 1, each group being guided by its own needle-plate *c*¹ *d*¹, the needles of each battery being arranged in a series of vertical rows seven to each row) with each row in alignment with the lifter-pegs of its complementary lifter, the needle disposition in relation to the "at rest" disposition of the pegs in the lifter system being such that the rearward displacement of any one needle (corresponding to a yarn-color selected by the jacquard card) by the operation of the grid will cause the lifter-peg complementary to that needle to be projected rearwardly from its brass into the path of an ascending lifting-bar and bring about the lifting of the selected yarn to the position in which a tuft of the same is cut off and transferred to the fell of the carpet.

The two superimposed batteries of horizontal needles *c* *d* are associated with and controlled by a single battery of vertical needles, indicated by *e* in Figure 1 and described in detail hereafter, whilst to provide for the actuation of the selected horizontal needles in the said batteries *c* *d* and for the raising of the lifters whose pegs are projected beyond their guide brasses by the rearward displacement of the said selected horizontal needles, the jacquard system embodies duplicated sets of contact-bars *f*¹ *f*² in the grid *f*, duplicating boards *g*¹ *g*² in the battery *g*, and duplicated lifting bars *h*¹ *h*² for respectively engaging or picking up the displaced pegs in the upper and lower rows of lifter brasses and imparting corresponding lift to the yarn-carriers. The groups of contact bars *f*¹ *f*² of the grid *f* correspond in number and vertical spacing to the horizontal needles in the upper and lower batteries *c* and *d* and are adapted to rearwardly displace any complementary needle which, by virtue of the card and vertical needle control, is permitted to remain in the path of its grid-bar when the grid is actuated, thus displacing in the same direction the lifter peg corresponding to the color selected by the card. Similarly, the boards *g*¹ *g*² of the dabbing mechanism are arranged in such relation to the horizontal needle batteries that, on the subsequent return of the raised lifters to their "at rest" positions, the said boards will restore or push back to their "at rest" positions those lifter-pegs that were displaced at the commencement of the cycle by the action of the grid, the corresponding horizontal needles being

returned to their normal positions by their springs.

The vertical spacing of the duplicated lifting bars or straight-edges h^1 , h^2 (which are coupled to work as a unit) is determined by the spacing of the rows of guide-brasses on the lifters and they (the lifting bars) provide for the raising of the needle-selected lifters and their yarn carriers through distances corresponding to the vertical relation of the projected lifter pegs to the stroke of the lifting-bar unit; it being obvious that if the lowest peg of any one brass is projected, it will be engaged by a lifting bar early in the stroke of the latter and provide for the maximum lift being transmitted to the corresponding yarn carrier, and that a less carrier lift is transmitted when a higher peg is projected since the lifter-bar then makes a longer idle stroke before picking up or engaging the peg.

As shown in Figure 1, both the upper and lower batteries of horizontal needles are controlled from the cards through a single battery of vertical needles e , each of which is interconnected with a complementary horizontal needle in either the upper or lower battery, the vertical needles being slidably suspended at the upper ends from stop-pins j^1 arranged across a needle-box j (see Figures 8, 9 and 10) in the head of the jacquard whilst their lower ends slidably engage in and are guided by perforations in a needle plate j^2 (see Figure 11) fixed across the frame between the lower battery of horizontal needles and the card-cylinder k .

To enable the necessary number of vertical needles to be compacted for accommodation in the same lateral space as the two horizontal batteries, particular formations of vertical needles and special dispositions of the same in relation to the horizontal needles are adapted. That is to say, in the seven-color control application of the invention now being described, the vertical needles are disposed in staggered rows across the width of the jacquard in the manner shown by the arrangement of their guide holes in the plan view of the needle guide-plate j^2 , Figure 11, the holes in the rows numbered 1, 3, 5, 7, 9, 11 and 13, being staggered relatively to the holes in the rows numbered 2, 4, 6, 8, 10, 12 and 14, and the needles that are guided by the holes in the odd-numbered rows are interconnected with and control complementary needles in the upper horizontal battery, whilst the needles guided by the holes in the even-numbered rows are interconnected with and control complementary horizontal needles in the lower battery as shown in the view of a part of the complete needle assembly Figure 12. The needles of the upper and lower horizontal batteries are thus controlled respectively by alternate rows of needles in the vertical battery.

This close or compacted disposition of vertical battery (which enables the use of narrower yarn carriers and a corresponding closer-pitched system of tuft-grippers) involves the formation of the needles of the two sets in a manner which will permit of each individual vertical needle effectively to control its complementary horizontal, and also to make its prescribed rise-and-fall movement without fouling the horizontal needles in either battery; this being realized by cranking the needles intermediate their suspension heads and the ends that work in the guide plate as shown in the general assembly, Figure 12, and also in the detail view, Figure 13. In this Figure 13 the needles numbered 1, 3, 5, 7, 9, 11 and 13, are a set adapted to control seven horizontal needles 1^a , 3^a , 5^a , 7^a , 9^a , 11^a , and 13^a , in the upper battery and the needles numbered 2, 4, 6, 8, 10, 12 and 14, are a set adapted to control horizontal needles 2^b , 4^b , 6^b , 8^b , 10^b , 12^b and 14^b , in the lower battery, and it will be seen from this view how the needles 1, 3, etc. controlling the top horizontals 1^a , 3^a , etc. are cranked at j^5 and j^6 to afford clearance for the needles in the lower horizontal battery and how the other needles, 2, 4, etc. controlling the lower horizontals 2^b , 4^b , etc. are cranked at j^7 in their upper parts to afford clearance for the needles in the top horizontal battery. This cranking of the vertical needles not only provides the clearance which enables each vertical to move without fouling or displacing any other needle than the one to which it is interconnected, but enables the loop or kink j^8 formed in each vertical needle for housing its complementary horizontal to be closed or bridged on its open side by a straight portion of an adjacent vertical needle as shown in the general assembly view, Figure 12. The loops in the vertical needles are thus completed and the correct location of the horizontal needles in their prescribed positions is ensured.

The suspension of the vertical needles in their "at rest" positions is provided for by arranging their head-stops j^8 normally to bear upon suspension pins j^1 disposed across the needle box as shown in Figures 8, 9, 10 and 12, and owing to the cranking of the needles which disposes the heads of two alternating rows into the same plane, both such rows can be suspended in common from a single stop-pin j^1 as shown in Figure 10, which enables the arrangement of an efficient construction of needle box with the same lateral space as the needle assembly. Twisting or rotational displacement of the vertical needles is prevented by providing a series of spacing wires j^{10} extending from side to side of the upper part of the needle box as shown in Figure 9 and arranging the stop-heads of the needles to slidably engage the spaces between these wires.

With regard to the suspension of the yarn-

carrier lifters in their "at rest" positions, the present practice is to extend the upper ends of the lifter-blades through slots in the top comb of the lifter-assembly and provide these extensions with stops or enlargements that drop onto the top of the comb and bring the lifters to rest after the same have completed their operations. Now since the lifters carry a considerable load and the comb is subjected to severe stress under the repeated impact of the falling lifter-stops, it is essential in the interests of efficiency and durability to make the comb of adequate strength to take the load and jar of the lifters, and to provide lifter stops having a substantial area of bearing surface on the comb, and to realize these desiderata in a jacquard according to the present invention where the available width of the comb-plate is required not to exceed the width of the needle assembly, it is proposed to construct and arrange the stop ends of the lifters and the comb-plate substantially in the manner hereinafter described with particular reference to Figures 3, 3^a, 4, 5, and 25 6 of the drawings.

That is to say, the suspension ends of the lifters are shaped into tongues a^4 , b^4 , of approximately half the full width of the blades (see Figure 4) and the extremities of these 30 tongues have stop-pieces a^1 , b^1 attached to the sides thereof; these stops being of a thickness equivalent to the pitching or lateral separation of the individual lifters. In each pair of lifters, the tongues are formed on the back 35 half of the one and in the front half of the other but both have the stop-pieces attached to the same side. For the accommodation and guiding of the lifters, the top comb-plate c is constructed as shown in Figure 6, of two halves c^1 , c^2 , cut with lifter-guide slots c^3 , c^4 which are adapted to accommodate the tongues a^4 , b^4 and are separated by widths of metal equivalent to the thickness of the lifter stops a^1 , b^1 . The two halves of the comb 40 are so assembled as to stagger the slots c^3 in relation to the slots c^4 and the lifters are arranged in pairs across the width of the assembly (see Figures 3 and 3^a) so that all the tongues a^4 of the successive pairs engage slots 45 c^3 on one side of the centre-line of the comb and all the tongues b^4 engage slots on the other side of the said centre-line; the stop-pieces of the two series of tongues alternately taking their bearings on the solid metal separating the slots. Thus notwithstanding that the parts of the lifters which engage the comb are substantially narrower than the parts that carry the lifter-peg brasses, the staggered arrangement of correspondingly-50 shorter guide-slots alternately on opposite sides of the comb-plate centre-line permits of the interposition of ample metal between the slots in the halves of the comb adequately 55 to take the load and impact of the lifters,

and provides also adequate areas of wearing surface on the comb and lifter-stops.

The construction of the top comb in halves slotted along their meeting edges permits of the ready assembly of the top comb with lifters to which the stop-pieces have already been attached to the sides of the tongues. The bottom comb is also made in halves o , o^1 , cut with registering sets of slots as shown in Figure 5 to accommodate the lifter-plates, and is mounted across the frame below the needle assembly. 70

Having described my invention, what I claim and desire to secure by Letters Patent is:—

1. A differential lift jacquard mechanism for tuft-fabric looms comprising a plurality of yarn carrier lifters, a lifter peg guide on each of said lifters, said guides being arranged in separated and superimposed rows, lifter-pegs carried in each of said guides and disposed in vertically spaced groups of horizontal rows, a group of horizontal jacquard needles for each group of lifter-pegs and similarly vertically spaced from one another, a lifting bar for each group of lifter-pegs and a dabbing board for returning any of the pegs of each group (displaced by the jacquard needles) to its inoperative position. 80

2. A differential lift jacquard mechanism for tuft-fabric looms comprising a set of yarn carrier lifters, a lifter-peg guide on each of said lifters, said guides being arranged in separated and superimposed rows and the guide on each lifter being arranged in a different row from the guides on the adjacent lifters, a plurality of lifter-pegs in each of said guides, a group of horizontal jacquard needles for each group of lifter-pegs and similarly spaced from one another, superimposed and separate groups of grid bars each acting on one of the groups of horizontal needles, a series of dabbing boards, each of which returns any displaced lifter-pegs in a row of guides to the inoperative position at the end of each loom cycle, and a series of lifting bars each acting on the displaced lifter-pegs in one of the rows of guides. 90

3. A differential lift jacquard mechanism for tuft-fabric looms comprising a set of yarn carrier lifters, a lifter-peg guide on each of said lifters, said guides being arranged in two separated and superimposed rows and the guide on each lifter being arranged in a different row from that on the adjacent lifter, a plurality of lifter-pegs in each of said guides, two separated and superimposed batteries of horizontal jacquard needles, each of which needles operates in conjunction with a lifter-peg in the corresponding row of lifter-peg guides, two superimposed and separate groups of grid bars each acting on a row of needles in the corresponding group of horizontal needles, two dabbing boards each of which returns any displaced lifter-pegs 100

in the corresponding row of lifter-peg guides to their inoperative position at the end of each loom cycle and two superimposed lifting bars each acting on the lifting pegs in 5 the corresponding row of lifter-peg guides.

4. A differential lift jacquard mechanism for tuft-fabric looms comprising a set of yarn carrier lifters, a lifter-peg guide on each of said lifters, said guides arranged in two separated and superimposed rows and the guide on one lifter being arranged in a different row from the guides on the adjacent lifters, two correspondingly separated groups of 10 horizontal jacquard needles and a single 15 group of vertical jacquard needles co-operating therewith.

5. A differential lift jacquard mechanism for tuft-fabric looms according to claim 4 in which the vertical needles are arranged in 20 staggered rows, the needles in alternate rows controlling the complementary needles in one of the superimposed batteries of horizontal needles.

6. A differential lift jacquard mechanism 25 for tuft-fabric looms comprising a set of yarn carrier-lifters, a lifter-peg guide on each of said lifters, said guides being arranged in two separated and superimposed rows, and the guide of each lifter being located in a 30 different row from that on the adjacent lifter, two correspondingly separated groups or batteries of horizontal jacquard needles each needle of which is controlled by one of a 35 group of vertical jacquard needles arranged in staggered rows, one group of horizontal needles being controlled by one set of alternate vertical needles, the other group of horizontal needles being controlled by the other set of alternate vertical needles, each of said 40 horizontal needles being carried by a loop or kink, formed in a corresponding vertical needle in one of the said alternate rows, which is closed by a cranked part of a needle in the other of the said alternate rows.

45 7. A differential lift jacquard mechanism for tuft-fabric looms comprising a set of yarn carrier lifters, a lifter-peg guide on each of said lifters, said guides being arranged in two separated and superimposed rows, and 50 the guide of each lifter being located in a different row from that on the adjacent lifter, two correspondingly separated groups or batteries of horizontal jacquard needles, each needle of which is controlled by one of a 55 group of vertical jacquard needles arranged in staggered rows, one group of horizontal needles being controlled by one set of alternate vertical needles, the other group of horizontal needles being controlled by the 60 other set of alternate vertical needles, each of said horizontal needles being carried by a loop or kink, formed in a corresponding vertical needle in one of the said alternate rows, which is closed by a cranked part of 65 a needle in the other of the said alternate

rows, and a needle box containing the heads of said vertical needles which are carried by stop pins, two rows, (one from each set of alternate vertical needles) being carried by each stop pin.

8. A differential lift jacquard mechanism for tuft-fabric looms comprising a set of yarn carrier lifters, a lifter-peg guide on each of said lifters, said guides being arranged in two separated and superimposed rows, and 75 the guide of each lifter being located in a different row from that on the adjacent lifter, a top comb-plate having guide and suspension slots located on opposite sides of its centre line wherein reduced ends of the lifters are housed, and stops on the said reduced ends, opposed to the metal at the side of the slots wherein the said ends are guided.

9. A differential lift jacquard mechanism 85 for tuft-fabric looms comprising a set of yarn carrier lifters, a lifter-peg guide on each of said lifters, said guides being arranged in separated and superimposed rows lifter-pegs carried in each of said guides and disposed in vertically spaced groups of horizontal rows, a group of horizontal jacquard needles for each group of lifter-pegs, a single group of vertical jacquard needles arranged in staggered rows, the needles in alternate rows controlling the complementary 95 needles in one of the groups of horizontal needles, a lifting bar for each group of lifter-pegs, and a dabbing board for returning any of the pegs of each group (displaced by the horizontal jacquard needles) to its inoperative position.

In witness whereof I affix my signature.
CECIL C. BRINTON.
